US0D111117S

(12) **United States Design Patent** (10) **Patent No.:** **US D1,111,117 S**
(45) **Date of Patent:** **** Feb. 3, 2026**

(54) **GOLF PUTTER HEAD COVER**

(71) Applicant: **QandB Co., Ltd.**, Gyeongsangbuk-do (KR)

(72) Inventor: **Min Kyu Park**, Gyeongsangbuk-do (KR)

(73) Assignee: **QandB Co., Ltd.**, Gyeongsangbuk-Do (KR)

(**) Term: **15 Years**

(21) Appl. No.: **29/958,148**

(22) Filed: **Aug. 19, 2024**

(30) **Foreign Application Priority Data**

Aug. 8, 2024 (KR) 30-2024-0031854

(51) **LOC (15) Cl.** **21-02**

(52) **U.S. Cl.**

USPC **D21/754**

(57) **CLAIM**

The ornamental design for a golf putter head cover, as shown and described.

DESCRIPTION

FIG. 1 is a perspective view of a golf putter head cover, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof showing a state in which the upper cover of the claimed golf putter head cover is open.

1 Claim, 6 Drawing Sheets
